UNITED STATES PATENT OFFICE.

BRIAN BERNARD GALLAGHER, OF ELDORADO, ILLINOIS.

RAIL ANCHOR AND TIE.

Application filed August 1, 1927. Serial No. 209,901.

This invention relates to improvements in railroad ties and to the means for fastening rails thereto, the general object of the invention being to provide means whereby the 5 rails can be easily and quickly locked to metal ties in such a manner that they will be firmly fastened to the ties through means of a locking action of the anchoring means which are pressed into locking position by a 10 press device so that the anchor means will act to hold the rails to the ties before such means are bolted to the ties and rails.

This invention also consists in certain other features of construction and in the 15 combination and arrangement of the several parts, to be hereinafter fully described, illustrated in the accompanying drawings and specifically pointed out in the appended claims.

20 In describing my invention in detail, reference will be had to the accompanying drawings wherein like characters denote like or corresponding parts throughout the several views, and in which:—

25 Figure 1 is a plan view of portion of a track constructed in accordance with this invention.

Figure 2 is a section on line 2—2 of Figure 1.

30 Figure 3 is a section on line 3—3 of Figure 1.

Figure 4 is a section on line 4—4 of Figure 3.

Figure 5 is a section on line 5—5 of Figure 1.

Figure 6 is a fragmentary plan view showing the joint between two rails.

Figure 7 is a section on line 7—7 of Figure 6.

40 Figure 8 is a section on line 8—8 of Figure 1.

Figure 9 is a perspective view of one end of a tie, a portion of a rail and the means for anchoring the rail to the tie.

45 In these views, 10 indicates the ties which are formed of channel iron with depending ends 11, a hole 12 being formed at each end of the tie. Each tie is also provided with a raised seat forming part 13 adjacent each end, the rails A of the track resting upon these seat forming portions. A pair of brackets 14 is fastened to each tie, each bracket abutting the inner edge of the seat 13 and said bracket extends over the inner 50 portion of the rail base and bears against the inner face of the web and has its upper

end bearing against the under part of the rail head. A member 15 is hingedly supported at each end of the tie by having its hinge part 16 extending into the opening 12, a hinge pin 60 or bolt 17 passing through the end of the tie and through said part 16. Each member 15 is also provided with a part for engaging the outer side of the base of the rail and another part for engaging the outer face of 65 the web thereof, with the upper end of said part bearing against the under side of the rail head. This member 15 is also provided with a lip 18 which extends slightly under the outer edge of the rail base, the 70 outer edge of the seat 13 being spaced from the outer edge of the rail base so as not to interfere with the lip.

The parts are so formed and arranged that in order to put a rail in position it must be 75 set on edge in a tilted position, as shown in Figures 1, 3 and 5, with the outer edge of the base of the rail fitting in the recess formed by the lip 18 of member 15. Then a press device B has its hooked member 19 80 placed in engagement with the flanges of the tie with the end of the screw 20 engaging the member 15. Then by turning the screw, said member 15 will be forced downwardly, carrying the rail with it until the rail rests 85 upon the seat 13 with its base securely gripped by the bracket 14 and the inner end of the member 15. Bolts or screws 21 are then passed through holes in the web engaging portions of the bracket 14 and member 15 and through a hole in the web and a bolt 22 is inserted in holes formed in the flat part of the member 15 and in the tie.

90 After the rail has been set in tilted position with the members 15 swung inwardly to engage the edge of the base of the rail, as shown in Figures 1 and 3, the clamp B can be placed on the tie which is located adjacent the center of the rail so that by pressing downwardly upon the member 15 of this tie, the rail will be forced downwardly upon its seat and it will carry the other members 15 with it. Thus a rail can be easily and quickly positioned. Then all the locking members are bolted in place.

95 When a rail is to be put in place at a curve, the hinge pins 17 are withdrawn and the curved rail is slipped under the brackets 14 so that the rail will rest upon the seats 13. Then the members 15 are placed on the ties 100 with their inner ends engaging the rail and they are forced into position by the use of 105 110

a crow bar or the like placed in the openings 12 and bearing against the parts 16. When the opening in the part 16 comes into register with the holes in the tie, the pin 17 is slipped into place and then the bolts are put in place as before.

The fish plates 23 for connecting the ends of the rails together have portions extending under the base of the rail, as shown in Figures 5 and 7, and these plates are arranged between a pair of the ties, as shown in Figure 6. One of these plates may be fastened to the rail already put in place so that the rail being put in place will occupy a tilted position in relation to said fish plate, as shown in Figure 5, but when the rail has been forced into an upright position by the press, the end thereof will enter the fish plate and then the second plate can be put in place, as shown in Figure 7.

This invention enables the parts to be used over and over again. As no spikes are used, there is nothing to hammer in position. The rails are supported from the base to the head and an entire rail may be snapped into place by the press in the time it takes to spike a rail to one tie. It also eliminates the use of base plates and all the parts of the track are securely connected together, and when the parts are pressed into position, the track is at the required gauge.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A track comprising metal ties each having a seat forming part adjacent each end thereof, rails engaging the seat forming parts, a pair of brackets fastened to each tie abutting the inner edges of the seat forming

parts and having portions engaging the rail base, the web and the under part of the head of the rail, a member hingedly connected with each end of each tie and having its inner end formed with a part to engage the rail base, the web and the head, means for fastening the rail to the brackets and said members and means for fastening said members to the tie.

2. A track comprising a plurality of metal ties having seat forming portions thereon for receiving the rails of the track, brackets fastened to each tie, shaped to receive parts of the inner sides of the rails, a member hingedly connected to each end of each tie and having its inner end shaped to receive portions of the outer side of a rail and a lip formed on each member and engaging the edge of the base of the rail so that the rail must be placed in tilted position against the brackets with the lips of the members engaging the under part of the base in putting the rail in place and then pressure applied to the member to force the rail upon its seat.

3. A track comprising a plurality of metal ties having seat forming portions thereon for receiving the rails of the track, brackets fastened to each tie, shaped to receive parts of the inner sides of the rails, a member hingedly connected to each end of each tie and having its inner end shaped to receive portions of the outer side of a rail, a lip formed on each member and engaging the edge of the base of the rail so that the rail must be placed in tilted position against the brackets with the lips of the members engaging the under part of the base in putting the rail in place and then pressure applied to the member to force the rail upon its seat and bolts for fastening the members and brackets to the webs of the rails and bolts for fastening the members to the ties.

In testimony whereof I affix my signature.
BRIAN BERNARD GALLAGHER.
